UNITED STATES PATENT OFFICE

2,542,387

SAFETY VALVE

Charles F. Boyer, Allentown, Pa.

Original application March 7, 1947, Serial No. 733,239. Divided and this application August 18, 1948, Serial No. 44,974

1 Claim. (Cl. 251—63)

1
This invention relates to safety valves, and more particularly, has reference to a safety valve arrangement for pneumatic tools.

The present application is a division of my co-pending application, filed March 7, 1947, and bearing Serial Number 733,239, now Patent Number 2,471,604.

The main purpose of the present invention is to provide a safety valve arrangement for pneumatic riveters or chipping machines, and related pneumatic tools. It has frequently happened that a riveting machine left unattended will be accidentally jarred from its position, as by someone accidentally tripping over the air supply hose leading to the tool. When this occurs, it may be that the tool is set into operation by accidental engagement of its trigger or operating lever. The tool is thus likely to rebound, since it is not being held, and strike nearby persons. This can and in fact has resulted in serious injury.

It is proposed to attain the objects of the invention by reason of the provision of a novel type of safety valve construction, whereby the possibility of the tool being accidentally set into operation will be eliminated.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Figure 1 is a view partly in elevation and partly in longitudinal section, through a pneumatic tool formed in accordance with the invention.

Fig. 2 is a section taken substantially on line 2—2 of Fig. 1.

Fig. 3 is a section taken substantially on line 3—3 of Fig. 1.

Fig. 4 is a section taken substantially on line 4—4 of Fig. 1.

Fig. 5 is a fragmentary perspective view of the sleeve valve and plug embodied in the invention.

Referring to the drawings in detail, the reference character 5 designates generally the head of the tool, which is of conventional formation, and is internally threaded for the purpose of receiving one end of the barrel (not shown).

The other end of the head 5 is closed, except for openings to be described hereinafter, and extended transversely across the closed end of the head is a tubular member 6, which is preferably

formed integral with the head 5, and with the handle 7 of the tool, that extends from one end of the tubular member 6 in a direction away from the head 5, and which is formed at its other end with the customary grip 8. The grip 8 is formed at one end with an opening 9 which is threaded in order to receive a coupling (not shown) with an air supply hose.

Recessed in one end of the handle 7, and mounted for reciprocation therein, is the thumb lever 26, that operates the main valve for the purpose of supplying air to the valve during normal use of the tool. The main valve and associated parts have been described in my parent application, Serial Number 733,239, and need not be discussed in detail herein. It is believed sufficient to state that under the control of the operator, in normal use of the tool air is permitted to enter the head of the tool through opening 31, communicating between the hollow interior of handle 7 and the bore of the tubular member 6.

Referring now to the construction of the safety shuttle valve, there is movably positioned in the adjacent bore of the tubular member 6 the sleeve or safety shut-off valve 32. One end of the sleeve 32 is open, and is engaged by the spring 33 which is interposed between said end of the sleeve, and the adjacent end of the tubular member 6. The other end of the sleeve 32 is closed, as shown at 34, and from this closed end is extended a socket 35, that is formed with a threaded opening 36 in which is engaged one end of a key 36'. The outer wall of the socket 35 is provided with opposed lugs 37, that are receivable in slots 38 formed in the inner end of the plug 39 that is threaded into one end of the tubular member 6, and closes the bore formed in said member, at that end.

Intermediate its ends, the sleeve 32 is formed with openings 40, that are adapted to be brought into communication with openings 41 provided in the closed end of the head 5. The particular formation and arrangement of my safety valve is such that when it is opened by the operator, it can not be accidentally closed. It is to be noted that in the operation of this valve, the user must first push the key 36' inwardly, in order to disengage the lugs 37 from the slots 38 formed in the inner wall of the plug 39. Having so disengaged the lugs 37, the key 36' may then be rotated, in order that the openings 40 will be brought out of register with the openings 41, the openings 41 thereby being closed off by the wall of the sleeve 32. Thus, no air can enter the barrel of the tool. It may

be noted that by rotation of the key 36', the lugs 37 are then brought to bear against the inner wall of the plug 39, and the key 36' is effectively prevented from being forced outwardly under the force of the spring 33, until it has been rotated so that the lugs 37 may enter the slots 38, at which time, the spring 33 will automatically force the key 36' outwardly and hold it in such position.

What is claimed is:

A safety valve for pneumatic tools comprising a sleeve having one end open to provide an air inlet and having the other end closed, said sleeve having a discharge opening formed in its side wall; a reduced extension formed on the closed end of the sleeve and having a centrally disposed threaded socket; diametrically opposed lugs formed on the side wall of said extension; a plug formed with a smooth bore counterbored to receive the extension, said plug having diametrically opposed recesses for receiving said lugs; an

operating key having a shank a portion of which is smooth for slidable and rotatable contact with the wall of the bore of the plug, the end of said shank being threaded and engageable in the threaded socket; and a spring engaging the open end of the tube and normally urging the tube in the direction of the plug.
